WILLIAM ACHESON SMITH, OF NIAGARA FALLS, NEW YORK, ASSIGNOR TO INTERNATIONAL ACHESON GRAPHITE COMPANY, OF NEW YORK, N. Y., A CORPORATION OF NEW JERSEY.

COMPOSITE ELECTRODE.

1,032,514.

Specification of Letters Patent. Patented July 16, 1912.

Application filed May 29, 1911. Serial No. 630,032.

To all whom it may concern:

Be it known that I, WILLIAM ACHESON SMITH, a citizen of the United States, residing at Niagara Falls, in the county of Niagara and State of New York, have invented certain new and useful Improvements in Composite Electrodes, of which the following is a specification.

This invention relates to electrodes for electro-thermic work, the object of the invention being the provision of an improved composite electrode.

It is often desirable in connection with electro-thermic operations to provide electrodes of large cross-sectional area, and consisting of conductive members of carbon or graphite in conjunction with a filling of lower electrical conductivity. According to the present invention electrodes of this character may be made of greater length than has heretofore been practicable, whereby a decided economy results, inasmuch as the necessary waste, in case the unused ends of the electrodes are rejected, is practically constant; and this waste bears therefore a diminishing proportion to the total as the length of the electrode is increased.

Certain preferred embodiments of the invention are illustrated in the accompanying drawing, wherein—

Figure 1 is a central longitudinal section of one form of electrode; Fig. 2 is a transverse section thereof on line II—II; Fig. 3 is a central longitudinal section of a modified form of electrode; and Fig. 4 is a transverse section thereof on line IV—IV.

The electrode illustrated in Fig. 1 comprises a central rod, bar or core, 1, 1, which is preferably of graphite or other highly conductive form of carbon, and a surrounding body 2 of lower electrical conductivity. This body 2 may consist of an initially plastic or fluid mixture of coke and tar, or of other carbonaceous material and binder, or of any suitable cement, concrete or mass

which is not objectionable in connection with the use to which the electrode is to be put. The conductive member consists of a plurality of sections 1, 1, which are joined end to end in such manner as to constitute a substantially continuous conductor. The joints may be of any desired kind, but are preferably so formed that they are adapted to be held firmly in place by the surrounding mass 2. This is simply and conveniently accomplished by a scarf or equivalent construction of the ends of the members 1, as indicated by the numeral 3.

In the construction illustrated in Figs. 3, 4 the conductive members 1^a, 1^a, are laterally exposed throughout their length, being embedded in the surface of the mass 2, but so interlocked therewith by means of their beveled edges 4, that the integrity of the joint is secured. This construction has the advantage that direct electrical contact may be made with the conductive members at any desired point in their length.

Obviously, the construction may be otherwise modified without departing from the spirit of the invention.

I claim:

1. A composite electrode consisting of a jointed conductive member or members, and a supporting body of lower electrical conductivity.

2. A composite electrode consisting of a jointed member or members of graphite, and a supporting body of lower electrical conductivity.

3. A composite electrode consisting of a jointed member or members of graphite, and a supporting body of non-graphitic carbon.

In testimony whereof, I affix my signature in presence of two witnesses.

WILLIAM ACHESON SMITH.
